IRVING LIEBER
BY Alwinburn
ATTORNEY

UNITED STATES PATENT OFFICE

134,363

DESIGN FOR A PIN OR SIMILAR ARTICLE

Irving Lieber, New York, N. Y.

Application February 11, 1942, Serial No. 105,765

Term of patent 3½ years

To all whom it may concern:

Be it known that Irving Lieber, a citizen of the United States and resident of New York, in the county of New York and State of New York, has invented a new, original, and ornamental Design for a Pin or Similar Article, of which the following is a specification, reference being had to the accompanying drawing, forming part thereof, in which,

Fig. 1 is a front elevational view of a pin embodying my new design; and

Fig. 2 is a side elevational view thereof.

I claim:

The ornamental design for a pin or similar article, substantially as shown.
